UNITED STATES PATENT OFFICE

2,391,518

FIRE GRATE

William L. Sharpe, Steubenville, Ohio, assignor to
The Ohio Foundry & Manufacturing Company,
Steubenville, Ohio, a corporation of Ohio

Application November 17, 1942, Serial No. 465,835

6 Claims. (Cl. 126—165)

This invention relates generally to fire grates and more particularly to basket type grates and firedogs for supporting burning fuel such as wood, coal and ceramics charged with or subjected to fluid fuels.

The principal object of this invention is the provision of a sectional grate structure for supporting burning fuel.

Another object is the provision of a grate in which the structure of the grate will absorb and radiate heat from burning fuel that it supports.

Another object is the provision of a sectional grate structure, the parts of which are capable of being assembled in different positions relative to one another for changing the form of the grate.

Another object is the provision of a number of parts which when assembled in block form produce a fire basket wherein the individual pieces are interlocked but not attached.

Another object is the provision of a ceramic grate structure, wherein such refractory materials as Missouri flint clay may be employed instead of the usual iron or steel, for the purpose of economy or for artistic reasons.

Other objects and advantages appear in the following description and claims.

Practical embodiments illustrating the principles of this invention are shown in the accompanying drawing wherein:

Fig. 1 is a top plan view of an assembled grate structure.

Fig. 2 is a side elevational view of the structure shown in Fig. 1.

Fig. 3 is an end elevational view of the structure shown in Fig. 1.

Fig. 4 is a perspective view of one of the intermediate sections of the grate structure similar to that shown in Figs. 1 and 2.

Fig. 5 is a perspective view of a unitary end member.

Fig. 6 is a partial view in section of the end member shown in Fig. 5 with two intermediate sections of the grate structure.

Fig. 7 is a view taken on a longitudinal section of a modified form of grate structure.

Fig. 8 is an end view of Fig. 7.

Fig. 9 is a perspective view of the grate support.

Fig. 10 is a perspective view of the end section of the grate structure shown in Fig. 7.

Fig. 11 is a partial isometric view of one of the grate bars shown in Fig. 7.

Fig. 12 is a view of a structure similar to that shown in Fig. 1 but assembled in an inverted position to produce a flat top grate structure.

Referring generally to the drawing, the grate structures shown are made up of a number of individual ceramic elements or members, some of which are duplicates of each other, that are constructed to fit and interlock with one another to form a complete grate capable of holding burning fuel. The shape of these ceramic members permitting them to interlockingly fit together and form a grate structure is one of the principal combinations of this invention. As shown in Figs. 1 to 3 the grate is carried on the spaced block or arch members 10 the feet 11 of which are sufficiently wide to provide a steady support for the structure. The ridge of each arch member is flat and has an upwardly extending projection or lug 12 at each end to prevent the support members or rails 13 from being shoved off their support. The rails 13 are preferably substantially square in cross section and may be provided with channels 14 on the under side that fit down over the ridge of the arch members to hold these four members in assembled relation. Each rail end has an upwardly extending head or projection 15 which in Figs. 1 to 3 engage the outer surface of 25 the end grate or tuyère members 16.

The end grate members 16 are rectangular par allelopiped with one side and the top hollowed out as shown at 17 to produce the concave end of the grate bowl. The end members 16 may be 30 duplicates as shown or one may have lugs along the inner lower edge for the purpose of spacing it from the next adjacent intermediate or tuyère member 18. An intermediate member 18 is shown in Fig. 4. This member is similar to the end member 16 with its side wall removed, thus providing a cross bar 19 with upwardly projecting ends 20 which produce a shape similar to the profile of the inner face of the end members.

Lugs 21 are formed on one side of the bar 19 40 of each intermediate member 18 for the purpose of holding them in spaced relation from the next adjacent member. In the form shown in Fig. 1 the intermediate member 18 in the center may be provided with lugs 21 on each side thereof. This 45 is an alternative form that may be employed instead of placing the lugs 21 on one of the end members.

The bottom of each of the end members 16 and the intermediate members 18 are provided 50 with aligned channels or grooves 22 which fit down over the rails 13. Thus each member is interlocked with the rails and the rails are in turn interlocked with the arch members 10 and the assembled parts form a grate which when the 55 end and intermediate members 16 and 18 are

hollowed out as described, produce a fire bowl or basket type grate.

In the structure shown in Figs. 5 and 6 the arch and end members 10 and 16 have been made integral with one another, producing a unitary end member 23. Square openings 24 are molded in the end members for receiving the heads 15 of the rails 13. The rails 13 and the intermediate grate bar members 18 are the same as those employed in Figs. 1 to 3. In assembling this structure the end members 23 are disposed at the proper distance from one another and the ends of the rails 13 are inserted through the openings 24 with their heads 15 extending downwardly to engage the outer surface of the end members and lock them in position. The intermediate members 18 are then positioned on the rails 13 with the grooves 22 fitting down over the same. Thus the pieces forming the structure of Figs. 5 and 6 are each interlocked with the rails in a manner similar to that described with reference to Figs. 1 to 3.

In the structure shown in Figs. 7 and 8 the ridge of each arch or support member 25 is made arcuate as shown at 26 in place of being flat as on the arch members 10. Thus the semicircular ridge portions of the support members 25 merge upwardly into the projections 12. The arcuate ridge 26 may follow a semi-cylindrical or semi-elliptical shape with a smooth curved surface or a series of short flat faces approximating a similar shape. The shape of the ridge 26 may vary in degree from the flat ridge of the arch member 10 to the arcuate ridge surface illustrated in Fig. 9.

A plurality of rails or grate bar members 27, the ends of which are shown in detail in Fig. 11, are provided with transversely disposed channels or grooves 14 on the under side for fitting down over the ridge 26 of the arch members 25 and the projections 12 prevent their outward lateral movement. Since the rails 27 in this instance form the grate bars they must be held in spaced relation. This may be accomplished by spaced lugs on the surface of the ridge 26 or by the lugs 28 on one side of the rails 27 as shown. The centermost rail need not be provided with spacing lugs 28.

The top surface of the ends of the rails 27 may be provided with closely spaced upwardly extending lugs 28 for receiving the end wall 30 which in Figs. 7, 8, and 10 is a plain flat plate substantially semi-circular in shape. If the rails 27 were employed on the arch members 10 of Fig. 1 the end wall 30 would take the shape of a rectangular bar. When the notches 14 of the rails 27 are engaged over the ridge of the arch members the spaced lugs 28 are disposed in alignment to receive the end walls and lock them in position. As previously pointed out all of the parts are interlocked with the rails to form a complete grate assembly. This type of grate is particularly advantageous for burning logs whereas the other two grate forms are better for coal.

To obtain a flat top grate with the pieces illustrated in Figs. 1 to 3 the arch members 10 are inverted and the notches 14 of the rails 13 are inserted over the feet 11, as shown in Fig. 12. The end members 16 and the intermediate members 18 are also inverted and placed on the rails 13, permitting the bowl to face downwardly with the transverse grate bars forming a flat top that can be used as a grate or a hot plate. The end members 16 in this view are prism shaped and

the head 15 is triangular to support the sloping back of the end member when it is turned with its concave portion turned upwardly as in Fig. 1. The side and end walls of these prisms shaped end members are of uniform thickness which is advantageous in a ceramic structure of this character.

The ceramic material from which these grate parts are molded is preferably a flint clay such as found in Missouri which has a high resistance to thermal and mechanical shock. Its shrinkage in drying and firing is low and it is capable of being made into rod form, such as the rails disclosed herein, which can withstand relatively heavy loads when cold or hot.

The use of a ceramic grate structure provides means for supporting the fire bed and at the same time furnishes a body that has the property of incandescence when heated for the purpose of 20 radiating heat energy which is not characteristic of the metal grates of this character. It has also been found that the ceramic grate is capable of retaining considerably more heat which aids in maintaining a fire in a grate structure of this 25 character in the open as contrasted to a fire pot or grate lined with fire clay.

Referring to Figs. 1 and 2, where wood logs are to be used as fuel, they may lay on the intermediate members 18, and, in case of logs of considerable length, the end members 16 may be removed and additional members 18 substituted, thus providing an open ended grate which will serve the purposes of andirons or dogs with the added advantage of intermediate support for the 35 logs.

In like manner if the end members 30 in Figs. 7 and 8 be removed, logs of considerable length may be burned with great convenience. Again 40 dogs or bricks may be substituted for arch members or end supports 10 and 25 in Figs. 2 and 7.

Furthermore where the distance between the end supports or arches is very considerable bricks or other suitable supports may be provided as intermediate undersupporting members for the 45 rails 13 or 27 in Figs. 2 and 7.

I claim:

1. A fire grate of assembled ceramic parts consisting of a set of support members arranged in parallel spaced relation to one another, a set 50 of grate bar members disposed transversely of and assembled on the support members, means on the grate bar members for maintaining them in spaced relation relative to each other, projections adjacent the ends of the support members for holding the grate bar members in assembled relation therebetween and to prevent their outward lateral movement, and spaced channels on each grate bar member which interlock with the support members to prevent the grate bar members from longitudinal movement.

2. The structure of claim 1 being further characterized in that the grate bar members extend upwardly to form the sides of a fire basket.

3. The structure of claim 1 being further 65 characterized in that the ends of the intermediate grate bar members extend upwardly to form the sides of a fire basket and the end grate bar members are each provided with an upwardly extending wall to form the ends of the fire basket.

4. The structure of claim 1 which also includes 70 a set of block members arranged in parallel spaced relation for carrying the support members, and channels on one set of members to interlock the support members with the block members.

5. The structure of claim 1 being further characterized in that the portions of the support members on which the grate bar members rest merge upwardly into said projections.

6. A fire grate comprising parallel spaced end walls, support members extending between the end walls and engaging the same, means on said support members engaging said end walls to prevent separation of the same, a set of grate bar members, disposed transversely of and assembled on the support members between the end

walls, means on the grate bars for maintaining them in spaced relation relative to each other and to permit downward passage of ash therebetween, spaced channel means on each grate bar interlocking with the support members to prevent the grate bar members from longitudinal movements, and said end walls and set of grate bars being formed of cast non-metallic moldable material.

10 WILLIAM L. SHARPE.
